Fig. 1

Fig. 2

Fig. 3

Fig. 4

FIG. 1 is a perspective view of a reflective hand signal for pedestrians showing my new design, the bottom and opposite side being substantially the same.

FIG. 2 is a side elevation thereof;

FIG. 3 is a perspective view of a modified form of the hand signal shown in FIG. 1, the bottom and opposite side being substantially the same; and

FIG. 4 is a side elevation thereof.

The stippled area shown in FIGS. 1 and 3 represents a conventional reflective surface.

This is a continuation of applications D. 62,044 and D. 62,046, both filed September 7, 1960, and both now abandoned.

I claim:

The ornamental design for a reflective hand signal for pedestrians, as shown and described:
